MACHINE FOR APPLYING LEGENDS TO SAFETY RAZOR BLADES

Irving S. Bodkin, New York, N. Y., assignor to
Conrad Razor Blade Co., Inc., New York, N. Y.,
a corporation of New York

Application October 27, 1943, Serial No. 508,094

13 Claims.

(Cl. 101—44)

1

The present invention relates to printing and etching and more particularly to a machine for applying a legend or design to safety razor blades although it may be utilized for other purposes.

Razor blades are manufactured from rolls of metal. The metal has a width corresponding to the width of the razor blade to be manufactured. The strip or ribbon of metal in the form of a roll may be fed into a machine from a roll on one side and may be formed into a roll at the discharge end of the machine. In this way the roll of metal may be subjected to various operations and finally the edges of the strip are ground and the strip is stamped into blade lengths forming individual safety razor blades which are then inspected and wrapped. The manufacturer usually desires to have his name or trade-mark or some legend or design on the finished blade. This is ordinarily done by applying an acid to the blade which etches the legend or design thereon.

The present invention aims to provide a simple, effective and efficient machine for applying acids and similar etching or printing materials to razor blades and like articles.

An object of the present invention is to provide an improved machine for applying etching materials to razor blades.

Another object of the invention is to provide a less expensive and more effective machine for applying legends or designs to razor blades.

Another object of the invention is to simplify the application of legends and designs to razor blades.

Other and further objects of the invention will be obvious upon an understanding of the illustrative embodiment about to be described, or will be indicated in the appended claims, and various advantages not referred to herein will occur to one skilled in the art upon employment of the invention.

A preferred embodiment of the invention has been chosen for purposes of illustration and description and is shown in the accompanying drawings, forming a part of the specification, wherein

Fig. 1 is a top plan view of a preferred embodiment of the machine;

Fig. 2 is an end elevational view of the machine;

2

Fig. 3 is a sectional view along the line 3—3 of Fig. 1 illustrating features of the legend applying mechanism;

Fig. 4 is a sectional view corresponding to Fig. 3 with the legend applying mechanism in engagement with the strip of metal for applying a legend;

Fig. 5 is an exploded view of the acid supply mechanism;

Fig. 6 is a sectional view along the line 6—6 of Fig. 1; and

Fig. 7 is a sectional view along the line 7—7 of Fig. 1 illustrating features of the mechanism for advancing the metal strip.

15 Described generally and with particular reference to Fig. 1 of the drawings, the machine comprises a guideway 1 for holding and guiding a strip of metal 2 to which legends are to be applied and which will later be formed into safety 20 razor blades. A reciprocating carriage 4 has a member 5 resiliently mounted thereon for advancing the strip step by step. A pair of applicators 7, having a suitable design or legend thereon, are pivotally mounted about pins 8 (Figs. 2, 1, 3 and 4) and are reciprocated toward and from the strip of metal 2 by pivoted levers 9, operated by cams 10 on drive shaft 11. During the retracting strokes the applicators 7 are oscillated into engagement with pads 12 (Figs. 3) supplied with acid 14 from reservoirs 15. The applicators 7 are brought into contact with the metal strip 2 during the period intermediate the advancing operations and while the strip is stationary. The several parts of the machine will now be described in more detail.

The guideway 1 (Figs. 1, 3, 4 and 7) comprises a channeled member 16 with shoulders 13 adapted to engage and support the sides of the strip 2 adjacent the edges thereof. The members 17 are secured to the legs of the channel member to hold the strip in position on the shoulders and to form a guideway for the strip of metal. Suitable guides 18 at the center of the channel may be provided for supporting the middle of the strip to facilitate the operation of the advancing means which will be described later. The channel member 16 may be secured to the frame 19 of the machine by a bracket 20. The portion of the guideway on the opposite

50 side of the frame 19 of the machine may com-

prise a member 21 having a recess 22 with grooves 24 at the upper and lower sides thereof for receiving the edges of the metal strip. Brackets 25 may support member 21 on the supporting frame 19. It will be noted that the guideway for the strip extends past the applicators 7 and the carriage 4 forming a part of the advancing mechanism.

Referring more particularly to Figs. 1 and 7 the channel member 16 has a member 26 bolted to its lower side and extending outwardly laterally of the channel member 16. A bar 27 is secured to the laterally extended part of the member 26 by screws 28. The carriage 4 is slidably mounted on the bar 27 by means of a channeled member 29 having surfaces engaging the upper and lower edges of the bar 27. Flange members 30 are secured to the channeled member 29 by screws 31 and extend over the edges of the bar 27 to hold the carriage in position thereon.

The advancing member 5 is pivotally mounted on a pin 32 (Figs. 1 and 7) at one end of the carriage and is held against a stop 34 by means of a leaf spring 35. As the carriage reciprocates back and forth the end of the resiliently mounted member 5 engages a slot or a perforation 33 in the strip 2 and advances the strip a predetermined distance, preferably the length of a blade or the length of a plurality of blades. In the preferred embodiment the strip is advanced the length of two blades during each forward movement of the carriage. On the return movement of the carriage the mounted member 5 acts as an idle pawl, being pushed back about its pivot 32 in opposition to the spring 35 by riding over the sides of the slots 33 in the strip without moving the strip in the opposite direction; in other words, the resiliently mounted member 5 engages the slots in the metal strip 2 to advance the strip in a step by step movement.

Any suitable means may be utilized for reciprocating the carriage 4 on the bar 27. As illustrated herein, an eccentric 36 is mounted on the drive shaft 11 and has a collar 37 with an extension 38 secured to a lever 39 pivoted at one end to a bracket 40 on the framework of the machine and connected at its other end to a link 41 attached to the carriage 4 by a bolt 42. As the drive shaft 11 rotates, the eccentric 36 thereon oscillates the lever 39 about its pivot 40 to reciprocate the carriage 4 and to advance the strip of metal through the machine.

Legends are applied to both sides of the strip 2 by identical mechanisms on the respective sides thereof. Hence, a description of one of the mechanisms will serve for both. A member 45 (Figs. 1, 3, 4 and 6) is slidably held in a channel of the member 46 by members 47 which are held in position by screws 48 and which extend over the edges of the member 45. The member 45 is reciprocated by means of a lever 9 pivoted at 49 to a bracket 50 secured to the frame 19 of the machine. One end of the lever 9 has a cam roller 51 operatively engaging the cam 10 on a drive shaft 11; the other end of the lever has a slot 52 engaging the upper end of a member 54 threaded into an adjustable member 55. The member 55 is secured to the slideable member 45 by means of a bolt 56 extending through a slot 57 in member 55 and threaded into the member 45. The member 55 has a downwardly extended part 58 at its protruding end with an adjustment screw 59 extending through it and threaded into an aperture in the end of the member 45. The adjustment

screws 56 and 59 may be utilized for changing the relative position of the members 45 and 55 to increase or decrease the amount of pressure applied by the applicator 7 to the strip of metal.

The ends of pin 8 (Figs. 1, 3 and 4) are held in position by the arms 60 of bracket 61 which is secured to the end of the member 45 by screws 62. A holder 64 is mounted on the ends of pin 8 and has a member 65 secured thereto by dove-tail joints 66. The applicator pad 7 is secured to the member 65 by an adhesive or in any other suitable manner. A coiled spring 67 extending about the pin 8, tends to retain the applicator 65 in the position shown in Fig. 4. As the slideable member 45, with the applicator thereon, is reciprocated into its retracted position a projection 69 on the applicator holder 64 engages a cam surface 70 on the member 71 projecting from bracket 72 secured to the stationary part of the machine by bolts 74 extending through slots, which permit adjustment of the parts. As the projection 69 moves along the cam surface 70 the holder 64 and the applicator 7 oscillate from the position shown in Fig. 4 to that shown in Fig. 3. In extended position the applicator 7 is in engagement with the strip of metal 2 and in retracted position it is in engagement with a pad 12 for replenishing the acid on it.

It will be seen that the reciprocation of the member 45 by means of the cam 10 and lever 9 presents the applicator 7 to the strip of metal 2 for applying a legend thereon while the strip is stationary and the applicator is thereafter retracted to permit movement of the strip and while retracted engages a pad for an additional supply of acid or other legend forming material.

A preferred mechanism for supplying acid to the applicator 7 is shown more particularly in Figs. 2, 3, 4 and 5. A reservoir 15 is provided with projections 76 operatively secured to the arms of the bracket 77 keyed to a shaft 78. An arm 79 is fixed to one end of the shaft with a cam roller 80 thereon in engagement with the member 81 on cam 10. The cam 10 engages the cam roller 80 during each revolution to raise the reservoir 15 and the parts thereof. The pad 12 may comprise a wick 82 extending down into the acid 14 in the reservoir. The wick may be held in position by means of a member 84 fitting over the open end of the reservoir and having slots or recesses 85 through which the wick may pass. Bars 86 may fit into the recesses to hold the wick in position. A suitable member 87 may fit into the channel of member 84 for supporting the portion of the wick extending thereover. In this way the acid travels up the end of the wick by capillary action and maintains a moist pad for engagement with the applicator 7. It will be noted that, when the applicator is in the position shown in Fig. 3, the cam 10 is effective on cam roller 80 to raise the reservoir 15 for supplying acid to the applicator. In this way there is no rubbing action between the applicator and the pad and an effective application is obtained.

Any suitable drive may be provided for the drive shaft 11, for example, a pulley 88 mounted on one end thereof may be driven by a suitable belt. The opposite end of the drive shaft 11 may have a hand wheel 89 for manual operation during the adjustment of the various parts. The shaft 11 may be mounted on brackets 90 secured to the framework of the machine.

In the operation of the machine the eccentric 36 on drive shaft 11 reciprocates carriage 4 to ad-

vance the strip 2 intermittently by means of a resiliently mounted member 5 which is effective to move the strip in one direction and ineffective to move it in the opposite direction. While the strip 2 is stationary the cams 10, effective upon the levers 9 at the opposite ends of the machine, reciprocate the members 45 inwardly toward the surface of the strip of metal 2. During this inward movement, the springs 67 and cam surfaces 70 oscillate the applicators 7 about the pins 8 to present the surfaces thereof to the opposite sides of the strip 2 for applying acid or other similar material thereto. The pressure of the applicator on the strip may be adjusted as desired by means of the adjustment screws 56 and 59. Upon the return stroke of the members 45 under influence of the spring 73 and cam 10 the applicators 7 are rotated by the cam surfaces 70 engaging the projection 69 to the position shown in Fig. 3. At this point the applicators are ready to receive a further application of acid. The acid reservoirs 15 are then raised by means of the members 31 on cams 10 engaging cam rollers 80 on arms 79 fixed to shafts 78, which carries the bracket 71. Thus prior to each application of the applicators to the strip 2 the surfaces thereof are brought into engagement with the pads 12 for replenishing the supply of acid thereon.

It will be seen that the invention provides a simple inexpensive and efficient means for applying designs or legends to articles such as razor blades. The parts are simple in construction, easy to operate and not likely to get out of order. A clear design is assured since the applicator pad is pressed against the stamp prior to each application thereof. There is no rubbing action between the pad and the stamp, thus minimizing wear. The applicator is applied to the metal strip while the latter is stationary and hence smearing is avoided and a sharp design is obtained. The legends and designs are accurately registered on the blades, since the metal strip is advanced and positioned by the blade slots. The machine is rugged in construction and fully capable of withstanding the rough usage to which it may be subjected.

As various changes may be made in the form, construction and arrangement of the parts herein without departing from the scope and spirit of the invention and without sacrificing any of its advantages, it is to be understood that all matter herein is to be interpreted as illustrative and not in a limiting sense.

Having thus described my invention I claim:

1. In a device of the class described, the combination with means for advancing a strip of material adapted to be formed into razor blades, of a guideway comprising edge guides for the strip leaving the sides of the strip exposed a pair of members mounted on the respective sides of said strip adjacent the guides, means to reciprocate said members toward and away from said strip, and means on said members for applying legends to the opposite sides of said strip, said means including applicators pivotally mounted on said members and cams for controlling the oscillating of said applicators about their pivots to present the effective surfaces thereof to the substantially opposite sides of said strip when said members are moved toward the strip, moistening devices, and means for moving both the applicators and moistening devices toward each other to present the effective surfaces of the applicators in contact with the moistening means during intervals when

said members are in retracted position with respect to said strip.

2. In a device of the class described, the combination of a guideway comprising spaced edge guides for a strip of material adapted to be formed into razor blades, a carriage movable longitudinally of said guideway and including strip engaging means adapted to advance said strip step by step, movable members mounted on opposite sides of said strip adjacent the spaced guides, means for reciprocating said movable members toward and away from said strip, and means on said movable members for engaging opposite sides of the strip intermediate the spaced guides and applying legends to the opposite sides of said strip during intervals while the strip is not being advanced.

3. In a device of the class described, the combination of a guideway comprising spaced edge guides for a strip of material adapted to be formed into razor blades, a carriage movable longitudinally of said guideway and having means to engage with and to advance said strip step by step, movable members mounted on opposite sides of said strip in the vicinity of said guides, means for reciprocating said movable members toward and away from said strip and means on said movable members for applying legends to exposed opposite sides of said strip between said guides when the strip is not advancing, said means including an applicator pivotally mounted on each of said members, and means for oscillating each of said applicators about its pivot to present the effective surfaces thereof to the sides of said strip when moved toward the strip a moistening pad for each applicator located adjacent a retracted position thereof, and means to move the effective surfaces of each applicator toward its pad during intervals when the applicators are retracted.

4. In a device of the class described, the combination of a guideway comprising spaced edge guides for a metal strip adapted to be formed into safety razor blades, means for advancing said strip periodically along said guideway, movable members adjacent said guides, means for reciprocating said movable members toward and away from said strip of material adapted to effect imprinting of the strip during intervals when it is not advancing, applicators carried by said movable members for applying a legend to said strip, and means for moistening the effective surfaces of said applicators prior to engagement with said strip, including moistening surfaces and means for moving said moistening surfaces into engagement with the applicators on said movable members.

5. In a device of the class described, the combination of a guideway having edge guides for holding a strip of material having perforations therein, a channeled back forming part of the guideway, and adapted to support the strip against side thrust, a carriage, means to mount said carriage for movement adjacent said guideways, devices for reciprocating said carriage, means on said carriage for engaging the strip at one side of a perforation and penetrating the perforation so as to be partly in the channel and effective for moving the strip in one direction and ineffective to move the strip in the other direction, and a further guideway comprising edge guides for the strip leaving the sides of the strip exposed to receive a marking device on both sides.

6. In a device of the class described, the combination of a guideway having edge guides for

holding a strip of material having perforations therein, a channeled back forming part of the guideway, and adapted to support the strip against side thrust, a carriage, means to mount said carriage for movement adjacent said guideway, devices for reciprocating said carriage, a pawl resiliently mounted on said carriage for engaging the strip at one side of a perforation and penetrating the perforation so as to be partly in the channel, said pawl being effective for moving the strip in one direction and ineffective to move it in the opposite direction, and a further guideway comprising edge guides for the strip leaving the sides of the strip exposed to receive a marking device on both sides.

7. In a device of the class described the combination of a guideway having edge guides for holding a strip of perforated material, a runway for a carriage adjacent said guideway, a carriage mounted on said runway, devices for reciprocating said carriage, a channeled back forming part of the guideway and adapted to support the strip against side thrust, means mounted on said carriage for engaging said strip through a perforation and entering the channel and effective to move the strip in one direction at predetermined intervals and ineffective to move it in the opposite direction, a further guideway comprising edge guides for the strip leaving the sides of the strip exposed, and reciprocating means movable in a direction substantially perpendicular to the movement of said strip for applying a legend to both sides of said strip intermediate said further guideway during periods when the strip moving means is ineffective to move the strip in said opposite direction.

8. In a device of the class described, the combination of a guideway comprising edge guides for a strip of material adapted to form razor blades, a carriage, means to mount said carriage for movement adjacent to said guideway, devices for reciprocating said carriage, means mounted on said carriage for engaging said strip and moving it in one direction in a step by step movement, and means at said guides for applying a legend to both sides of said strip comprising a reciprocating member at each side of the strip and an applicator pivotally mounted thereon and adapted to be pressed against the strip during time intervals when the strip is not being moved by the strip engaging means and to be thereafter moved away from the strip.

9. In a device of the class described, the combination of a guideway having edge guides for a strip of material adapted to be formed into razor blades, a channeled back forming part of the guideway and adapted to support the strip against side thrust, a carriage, means to mount said carriage for movement adjacent to said guideway, devices for reciprocating said carriage, means mounted on said carriage for engaging perforations on said strip and entering the channel to move the strip in one direction in a step by step manner to provide periods of rest and movement, a further guideway comprising guides for the strip leaving the sides of the strip exposed, and means for applying a legend to both sides of said strip intermediate the edge guides of said further guideway including a member on each side of the strip movable in a direction substantially perpendicular to said strip in the vicinity of said further guideway, a pivotally mounted applicator thereon, and means for rotating said applicator to apply a legend forming material to the applicator in one position and to engage

the strip in another position during periods when the strip is at rest.

10. In a device of the class described, the combination of means for intermittently advancing a strip of material, a guideway comprising edge guides for the strip leaving the sides of the strip exposed, a movable member, means for reciprocating said member toward and away from said strip of material in timed relationship with respect to said intermittent advancement of the strip, an applicator pivotally mounted adjacent one end of the movable member, a material-applying pad, resilient means operatively associated with said applicator, and cam means stationary with respect to said movable member adapted to co-operate with said resilient means to move said applicator about its pivot to present the effective surface thereof to said strip of material adjacent said guides when reciprocated toward the strip of material and during intervals when the strip is not advancing and adapted to move the applicator about its pivot to present said effective surface toward the material-applying pad when in retracted position.

25 11. In a device of the class described including means for intermittently feeding a continuous metallic strip and means for applying a legend-forming material to the strip during periods while the strip is at rest, a reservoir disposed adjacent an imprinting position of the device, a length of fluid-conducting material having end portions thereof extending into said reservoir, backing means supporting a portion of said fluid-conducting material above the surface of a fluid in said reservoir, and applicator means adapted to contact said length of fluid-conducting material above said backing means to receive fluid thereon and movable into contact with the side of said continuous metallic strip while the strip is at rest.

40 12. In a device of the class described including means for intermittently feeding a continuous metallic strip and means for applying a legend-forming material to the strip during periods while the strip is at rest, reservoirs disposed adjacent an imprinting position of the device, lengths of fluid-conducting material having end portions thereof extending into said reservoirs, backing means supporting portions of said fluid-conducting material in substantially horizontal positions above the surfaces of a fluid in said reservoirs, and a separate reciprocable applicator means adapted to contact said lengths of fluid-conducting material above said backing means upon retraction of the applicator means with respect to the strip and to receive fluid thereon and movable into contact with opposite sides of said continuous metallic strip while the strip is at rest.

60 13. In a device of the class described, the combination of a guideway comprising spaced edge guides for holding a continuous strip of material exposed on both sides, means for moving said strip through said guideway a predetermined distance at predetermined spaced time intervals, members mounted at opposite sides of the path of movement of said strip, means for reciprocating said members toward and away from said path, applicators pivotally mounted on the adjacent ends of said members, fluid-supplying devices positioned adjacent the path of movement of said applicators, and means responsive to reciprocating movement of the members for swinging said applicators into contact relationship with said devices during a portion of the movement

of the members and for swinging them into facing relation with the sides of the strip for contact therewith during another portion of said movement while the strip is at rest.
